UNITED STATES PATENT OFFICE.

ALBERT F. B. HENNIG, OF DENVER, COLORADO.

STREET-LAMP.

SPECIFICATION forming part of Letters Patent No. 339,884, dated April 13, 1886.

Application filed December 23, 1885. Serial No. 186,542. (No model.)

To all whom it may concern:

Be it known that I, ALBERT F. B. HENNIG, of Denver, in the county of Arapahoe and State of Colorado, have invented a new and useful Improvement in Street-Lamps, of which the following is a full, clear, and exact description.

The object of my invention is to provide certain new and useful improvements in street-lamps, whereby the gas is automatically turned on by swinging up the bottom gate or door to introduce the torch or other light used for igniting the gas.

The invention consists in the construction and combination of parts and details as will be fully described and set forth hereinafter, and then pointed out in the claims.

Reference is to be had to the accompanying drawings, forming a part of this specification, in which similar letters of reference indicate corresponding parts in both the figures.

Figure 1 is a cross-sectional view through the lower part of a lamp provided with my improvement. Fig. 2 is a plan view of the same.

The burner-tube A, of the usual construction, is provided with the cock B, which is also of the usual construction, and is provided on the outer end of its stem C with the ratchet-wheel D. The two levers E are mounted to rock on the stem C, at opposite sides of the ratchet-wheel D, and have their swinging ends pivoted to the link F, which is pivoted to the upper surface of the door G, pivoted in the bottom of the lantern-frame J, to swing upward. Between the two levers E the pawl K is pivoted, which rests on the rim of the ratchet-wheel D, and can engage with the teeth of the same. The door G is provided with the recess L in its inner edge, to permit it to swing upward without interfering with the burner-tube.

The operation is as follows: The lamp-lighter strikes the bottom of the door G with the end of the cap on his torch and swings the said door upward, as shown in dotted lines in Fig. 1, whereby the pawl K is swung into the position shown in dotted lines, and by means of the ratchet-wheel D turns the cock B open, to permit the gas to issue from

the end of the burner, and then the gas is ignited by means of the torch. The gate then swings down without affecting the position of the cock. When the gas is to be shut off, the door G is again swung up in the manner 55 stated, and thereby the cock B is given another quarter-turn and the burner is closed.

My improvement can be applied on any gas-lamp and on any burner.

Having thus fully described my invention, I 55 claim as new and desire to secure by Letters Patent—

1. The combination, with a lamp-frame, a gas-burner, and its cock, of a swinging door on the frame, a lever mounted loosely on the 65 stem of the cock and connected to the door, and intermediate devices between the said lever and cock for turning the latter when the door is opened, whereby provision is made for turning on and off of the gas by the opening of the door, substantially as described.

2. The combination, with a lamp-frame, a swinging door on the same, a gas-burner therein, and its cock, of a ratchet-wheel on the cock, a lever pivoted to the burner and 75 connected to the door, and a pawl pivoted to the lever and engaging the ratchet-wheel, substantially as and for the purpose set forth.

3. The combination, with a lamp-frame, a swing-door on the same, a burner therein, and 80c its cock, of a ratchet-wheel on the stem of the cock, levers pivoted on the stem of the cock, a link connected to said levers and door, and a pawl pivoted to said levers and engaging the ratchet-wheel, substantially as herein 85 shown and described.

4. The combination, with a lamp-frame, of a swinging door in the bottom part of the same, a ratchet-wheel on the stem of the cock of the burner in said lamp-frame, levers 90 mounted to swing on the stem of the cock, a link connected with the said levers and with the door, and of a pawl pivoted to said levers and engaging with the ratchet-wheel on the stem of the cock, substantially as herein shown 95 and described.

ALBERT F. B. HENNIG.
